GUN SYNCHRONIZER

Application filed April 2, 1930. Serial No. 440,893.

This invention relates to a machine gun synchronizer unit, and more particularly to a cam impulse generator.

The object of this invention is to provide a more compact arrangement of a synchronizer and an improved means of maintaining proper alignment between the cam and its follower.

With the foregoing and other objects in view, the invention resides in the combination of parts and in the details of the construction, hereinafter set forth in the accompanying specification and appended claims, certain embodiments of the invention being illustrated in the accompanying drawings, in which:

Figure 1 is a view in a longitudinal section through the device, and

Figure 2 is a view partly in longitudinal section through the device taken on a plane at right angles to that shown in Figure 1.

Figure 3 is a detailed view showing the follower and a particular type of cam with one lobe and the follower.

Figure 4 is a similar detailed view of a modification of the follower and a tangential cam with two lobes.

It is a common practice to provide means whereby a machine gun mounted on an airplane may be so synchronized with an internal combustion engine, and with the rotation of the propeller driven thereby, that the gun may be discharged at frequent intervals through the path of rotation of the propeller without interference.

Referring more particularly to the drawings, there is provided such a synchronizer unit comprising a casing 1 in which there is mounted a shaft 2 which may be driven through its integral bevel gear 3 by the airplane engine. A ball bearing assembly is provided for the rotation of the shaft and consists in the outer races 4 journaled in a sleeve 5 secured to the casing by set screws 6, and inner races 7 secured with the shaft, the races being held against the longitudinal movement by an intervening sleeve 8 and an end nut 9 engaging the shaft, and by the inwardly depending flange 5' of the sleeve 5.

Suitably keyed to and arranged interiorly

of the shaft 2 at 22 is a shaft 10 with an enlarged portion recessed to receive a ball bearing assembly 11 and screw threaded to receive a retaining nut 12. The shaft 10 terminates in an integral cam 13 which may be of the type shown in Figure 3 or a single or double lobed tangential cam shown in Figure 4. The camshaft runs at twice the engine speed to fire with a two-blade propeller, or which may be a double-lobe cam, as shown in Figure 4, in which case the cam shaft turns at engine speed.

A cam follower 14, which forms the prime mover of the gun actuation means, is journaled within an extension of the casing for reciprocal movement in a direction at right angles to the axis of rotation of the shaft and against the action of the spring 21. The follower is recessed to form straight horizontal end faces 15 and 16 and longitudinal face 17, and the recess is of a greater length than the largest diameter of the lobed cam.

The function of the cam is to operate the cam follower in a direction indicated in Figure 2 as a downwardly one. Accordingly the face 16 is rounded, as shown in dotted lines in Figures 3 and 4, to receive impacts from the lobe, or lobes, of the cam when the shaft 10 is rotated. The cam follower is returned by means of the spring 21 which is of such capacity as to hold the cam follower in contact with the cam at all operating speeds.

The upper end of the cam follower is provided with a slot 20 which may be so arranged as to be caught by a suitable sliding pin operated by a trigger. As will be readily understood without actual disclosure, when the pilot desires to fire his machine gun, he pulls a trigger which will pull a pin out of engagement with the notch 20 in the cam follower. This permits the spring 21 to force the face 16 of the follower against the cam, and the follower thus receives regularly timed impulses from the cam until such time as the slot 20 is engaged by a pin to hold the cam follower out of engagement with the cam. The distance between the faces 15 and 16 is such that allows sufficient clearance under these conditions for the cam to rotate without

striking either of the faces 15 and 16 of the follower.

Alignment of the tangential cam and the follower is maintained by means of a plurality of adjusting screws 19 in order also to provide for the proper clearance between face 17 of the follower and the outer face 18 of the cam.

Having thus described my invention, I claim:

1. In a device adapted for use as a machine gun synchronizer, a shaft adapted to be driven by prime mover, a shaft located within said first shaft and driven thereby, said second shaft terminating in an integral cam, a spring returned cam follower adapted to function as an impulse generator for the firing mechanism of said machine gun, said follower having formed therein a longitudinal recess with end faces, said cam being adapted to rotate within said recess and strike one of said end faces to cause a reciprocation of said follower against the action of said spring, set screws being provided for the purpose of maintaining said cam in alignment with said follower.

2. In a device adapted for use as a machine gun synchronizer, a driven shaft with a cam arranged thereon and capable of swivel adjustment, a cam follower adapted for use as an impulse generator for the firing mechanism of said machine gun, said follower being so recessed as to permit rotation of said cam therein and to be thus actuated by said cam for causing reciprocatory movement of said follower, said driven shaft and cam being alignable with said follower.

3. In a device adapted for use as a machine gun synchronizer, a driven shaft with a cam arranged thereon and capable of swivel adjustment, a cam follower adapted for use as an impulse generator for the firing mechanism of said machine gun and notched to receive a suitable releasable restraining member, said follower being sufficiently spring actuated when said follower is released from restrained position, to force the follower upwardly into constant contact with said cam during the rotation of the latter, said driven shaft and cam alignable with said follower.

4. In a device adapted for use as a machine gun synchronizer, a driven shaft with a cam arranged thereon and capable of swivel adjustment, a cam follower adapted for use as an impulse generator for the firing mechanism of said machine gun, said follower having formed therein a longitudinal recess with end faces, said follower being notched to receive a restraining member and said recess being of sufficient length to allow the rotation of the cam therein under these conditions without striking either of said end faces, said follower being provided with a spring for forcing the lower end face into constant engagement with said rotating cam upon the

release of said notch by the restraining member, said driven shaft and cam being alignable with said follower.

5. In a device adapted for use as a machine gun synchronizer, a driven shaft with a cam arranged thereon and capable of swivel adjustment, a cam follower adapted for use as an impulse generator for the firing mechanism of said machine gun, said follower having formed therein a longitudinal recess with end faces, said follower being notched to receive a restraining member and said recess being of sufficient length to allow the rotation of the cam therein under these conditions without striking either of said end faces, said follower being provided with a spring for forcing the lower end face into constant engagement with said rotating cam upon the release of said notch by the restraining member, a plurality of set screws being provided for the purpose of maintaining said cam in alignment with said follower, said driven shaft and cam being alignable with said follower.

6. In a device adapted for use as a machine gun synchronizer, a hollow rotary driving shaft adapted to be actuated by a suitable prime mover, a driven shaft keyed to said driving shaft and adapted to be rotated thereby, a tangential cam arranged on one end of said driven shaft, and means for maintaining said driven shaft in adjusted positions made possible by said key connection, a cam follower adapted for use as an impulse generator for the firing mechanism of said machine gun, said follower being so recessed as to permit rotation of said cam therein and to be thus actuated by said cam for causing reciprocatory movement of said follower.

7. In a device adapted for use as a machine gun synchronizer, a hollow rotary driving shaft adapted to be actuated by a suitable prime mover, a driven shaft keyed to said driving shaft and adapted to be rotated thereby, a tangential cam arranged on one end of said driven shaft, and means for maintaining said driven shaft in adjusted positions made possible by said key connection, a cam follower adapted for use as an impulse generator for the firing mechanism of said machine gun and notched to receive a suitable releasable restraining member, said follower being sufficiently spring actuated when said follower is released from restrained position, to force the follower upwardly into constant contact with said cam during the rotation of the latter.

8. In a device adapted for use as a machine gun synchronizer, a hollow rotary driving shaft adapted to be actuated by a suitable prime mover, a driven shaft keyed to said driving shaft and adapted to be rotated thereby, a tangential cam arranged on one end of said driven shaft, and means for maintaining said driven shaft in adjusted positions

- made possible by said key connection, a cam follower adapted for use as an impulse generator for the firing mechanism of said machine gun, said follower having formed therein a longitudinal recess with end faces, said follower being notched to receive a restraining member and said recess being of sufficient length to allow the rotation of the cam therein under these conditions without striking either of said end faces, said follower being provided with a spring for forcing the lower end face into constant engagement with said rotating cam upon the release of said notch by the restraining member.
9. In a device adapted for use as a machine gun synchronizer, a hollow rotary driving shaft adapted to be actuated by a suitable prime mover, a driven shaft keyed to said driving shaft and adapted to be rotated thereby, a tangential cam arranged on one end of said driven shaft, and means for maintaining said driven shaft in adjusted positions made possible by said key connection, a cam follower adapted for use as an impulse generator for the firing mechanism of said machine gun, said follower having formed therein a longitudinal recess with end faces, said follower being notched to receive a restraining member and said recess being of sufficient length to allow the rotation of the cam therein under these conditions without striking either of said end faces, said follower being provided with a spring for forcing the lower end face into constant engagement with said rotating cam upon the release of said notch by the restraining member, a plurality of set screws being provided for the purpose of maintaining said cam in alignment with said follower.
10. In a device adapted for use as a machine gun synchronizer, a hollow rotary driving shaft adapted to be actuated by a suitable prime mover, a driven shaft keyed to said driving shaft and adapted to be rotated thereby, a tangential cam arranged on one end of said driven shaft, and means for maintaining said driven shaft in adjusted positions made possible by said key connection, a cam follower adapted for use as an impulse generator for the firing mechanism of the gun, said follower being so recessed as to permit rotation of said cam therein and to be thus actuated by said cam for causing reciprocatory movement of said follower and means for adjusting and maintaining said cam in alignment with said follower.

In testimony whereof, I have signed my name to this specification this 24th day of March, 1930.

WINTHROP S. HORTON.
